UNITED STATES PATENT OFFICE.

EARL B. GRAHAM AND RALPH E. KIRKHAM, OF BELLINGHAM, WASHINGTON.

LARD SUBSTITUTE.

1,218,758.

Specification of Letters Patent. Patented Mar. 13, 1917.

No Drawing.

Application filed December 14, 1916. Serial No. 136,894.

To all whom it may concern:

Be it known that we, EARL B. GRAHAM and RALPH E. KIRKHAM, citizens of the United States, and residents of Bellingham, 5 in the county of Whatcom and State of Washington, have invented a certain new and useful Lard Substitute, of which the following is a specification.

Our composition consists of the following 10 ingredients: beef oil, obtained from rendering beef suet, and Argo oil obtained from Indian corn as manufactured by the Corn Products Company of New York city. These materials we combine in the following 15 proportions: beef oil 2 parts and Argo oil 3 parts.

We prefer to use the following method in combining these materials: Selected beef suet is rendered in an open kettle and the 20 oil separated from the solids by straining and pressing. When the beef oil is still hot the Argo oil is added in the above proportion, the temperature of the combination being about 240° F. Then the mixture is

cooled to about 95° F. and placed in a mechanical agitator and agitated until it falls to a temperature of about 85° F. The material is then removed from the agitator and placed in the containers in which it is to be sold; said containers remaining uncovered 25 for about 10 hours. Said filled containers are then sealed, or simply covered, and are ready for market.

Having thus fully described our new composition, what we claim as new and desire to 30 secure by Letters Patent is,

The combination of beef oil and corn oil in the proportion of 2 parts of said beef oil and 3 parts of said Argo oil.

Signed at Bellingham, in the county of 40 Whatcom and State of Washington this 9th day of December, A. D. 1916.

EARL B. GRAHAM.
RALPH E. KIRKHAM.
